SOAKING PIT CRANE

Robert J. Harry, Alliance, Ohio

Application October 24, 1940, Serial No. 362,593

7 Claims. (Cl. 212—11)

This invention relates to lifting cranes and, in particular, to cranes for placing steel ingots in a soaking pit and removing them therefrom.

Soaking pit cranes have heretofore been of two principal types, i. e., the "high" and the "low" type, these terms referring generally to the amount of head room required by cranes of the two types. The conventional "high" type crane comprises a trolley adapted to traverse a crane bridge and having a vertically reciprocable rack column slideable in a tower-like structural guide frame extending a considerable distance above and below the trolley, the rack column having ingot-gripping tongs at its lower end. In the "low" type crane, the structural frame in which the column reciprocates depends below the trolley. In both types, the presence of the guide frame adds materially to the cost and weight of the crane. A further objection to the conventional construction is that when the guide frame strikes an obstacle such as an ingot or mold, as sometimes happens, despite the greatest care on the part of the operator, the stress of impact is transmitted directly to the crane because of the rigid mounting of the frame on the trolley. In the "low" type crane, furthermore, rotation of the tongs is effected by a motor mounted on the reciprocating column and flexible cables are necessary to supply energy to the motor. These cables are difficult to maintain in good operating condition. The operator's platform, in the "low" type crane, is disposed below the traveling bridge to provide good visibility, but this brings the operator objectionably close to the furnace when charging or removing ingots.

I have invented a novel type of crane particularly adapted for soaking pit service, which overcomes the aforementioned objections to such cranes as constructed heretofore. In a preferred embodiment of the invention, I eliminate the conventional guide frame altogether and provide a lifting block adapted to be suspended below a trolley movable along a traveling bridge. Tong-actuating means carried by the block cooperate with tongs pivoted adjacent the lower end of a shaft depending from the trolley and extending through the block. The shaft also extends through a guide mounted on the trolley for universal movement. A motor and a suitable drive for turning the shaft are mounted on the guide. A second block below the trolley is adapted to raise or lower the shaft, thereby causing opening or closing of the tongs. Cables traversing the sheaves of both blocks are secured at one end to a drum on the trolley. The other ends of the

cables traversing the sheaves of the shaft-supporting block are secured to another drum on the trolley, while the other ends of the cables traversing the sheaves of the lifting blocks are secured to anchorages on the trolley. Thus by operating the first-mentioned drum the crane may be raised or lowered. By operating the second drum only, the tongs may be actuated. Restoring springs tend to hold the shaft normally in substantially vertical position.

The preferred embodiment of the invention outlined above is illustrated in the accompanying drawings to which reference is made for a detailed description. In the drawings:

Fig. 1 is a side elevation with parts broken away;

Fig. 2 is a partial sectional view taken along the plane of lines II—II of Fig. 1 showing parts in elevation;

Fig. 3 is a plan view with parts omitted for the sake of clearness;

Fig. 4 is a partial sectional view taken substantially along the plane of line IV—IV of Fig. 1; and

Fig. 5 is a vertical central section through a modified form of universal mounting, showing the shaft guide therein in elevation.

Referring now in detail to the drawings, a trolley 10 comprises a frame 11, conveniently a casting having box-like cross members 12 and 13 at opposite ends thereof providing journal boxes for stub shafts 14 and a through shaft 14' on which wheels 15 are disposed. The wheels 15 travel on rails 16 secured to the girders 17 of a traveling crane bridge of any suitable construction. (The girders are omitted from Fig. 3).

The frame 11 has a floor or deck 18. A motor 19 secured to the deck is coupled to a shaft journaled in a gear case 20 on which a pinion 21 is keyed. The pinion 21 meshes with a gear 22 keyed to an auxiliary shaft journaled in the case 20. A pinion 23 keyed to the same shaft as the gear 22 meshes with a gear 24 on the shaft 14'.

By virtue of the mechanism described, operation of the motor 19 causes the trolley 10 to travel along the rails 16.

A block housing 25 is suspended below the trolley 10. The housing comprises side plates 26, end walls 27, and a cover 28. The side plates 26 are welded at their lower ends to a casting 29 comprising spaced sheave blocks 30 and 31 and a hub 32 therebetween. Sheaves 33 are journaled on pins 34 in the blocks and are traversed by cables 35. As shown in Fig. 1, one end 55 of each of the cables 35 is secured to a drum 36

on the trolley, while the other ends of the cables are secured to anchorages 37 on the trolley. Each of these anchorages comprises a ball 38 disposed in a split spherical seat on the transom 13, a bolt 39 having a clevis at one end to which the cables are secured, and a spring cushion 40 on the other end. The cushions 40 extend through holes 40' in the deck 13.

The drum 36 is journaled in bearings 41 and 41' on the car and is driven by a motor 42 also mounted thereon. The motor 42 is coupled to the worm shaft 43 of a worm reduction gear 44 including also a worm wheel 45. The worm wheel is keyed to a shaft 46 journaled in bearings 47 and 47'. Pinions 48 in gear cases 49 are keyed to the shaft 46 and mesh with gears 50 formed integral with the drum 36. A cable slot 51 is formed in the deck 18 of the trolley to receive the cables 35. The motor 42 is provided with a brake 52 and the drum 36 with a brake 53 of known construction.

A casting 54 comprising spaced sheave blocks 55 and 56 and a hub 57 therebetween is movable in the upper portion of the housing 25. Sheaves 58 are journaled on pins 59 in the blocks 55 and 56, the outer ends of the pins projecting through windows 60 in the end walls 27 of the housing, thereby limiting movement of the casting in the housing. Cables 61 traverse the sheaves 58. One end of each cable is secured to the drum 36. The other ends of the cables 61 are secured to a drum 62. The drum 62 is journaled on bearings 63 and 63' on the deck 18 of the trolley 10 and is driven by a motor 64 through a worm reduction gear 65. The motor is coupled to the worm shaft 66 of the reduction gear which has a worm meshing with a worm wheel 67 keyed to a cross shaft 68 journaled in the reduction gear and in a gear case 69. A pinion 70 is in the case 69 keyed to the shaft 68 and meshes with a gear 71 formed integral with the drum 62. A brake 72 is provided at the free end of the worm shaft 66.

It will be understood from the foregoing that operation of the motor 42 while the drum 62 remains stationary will cause the drum 36 to take up or pay out both cables 35 and cables 61 at the same rate, thereby raising or lowering the blocks 30, 31 and 55, 56 at the same rate, i. e., without changing their relative positions in the housing 25. On the other hand, operation of the motor 64 while the drum 36 is stationary will cause the drum 62 to take up or pay out the cables 61 without affecting the cables 35, thereby raising or lowering the blocks 55, 56 in the housing 25. I utilize this movement to effect operation of ingot-gripping tongs about to be described.

A sleeve 73 has a reduced upper end inserted in the hub 32 of the casting 29 forming part of the block housing 25. The sleeve is rotatably supported in the hub on a thrust bearing 74, a washer 75 and a nut 76 on the upper end of the sleeve transmitting the vertical load on the latter to the bearing.

Ingot-gripping jaws 77 are pivoted at 78 on a cross-head 79. The cross-head 79 is secured by a key 80 to a shaft 81. The shaft 81 extends downwardly through a guide 82, through the hub 57 of casting 54 and through the sleeve 73. Rearward extensions 83 on the jaws 77 have rollers 84 cooperating with oppositely inclined surfaces 85 formed on the sleeve 73. By this construction, the jaws are actuated to their closed positions indicated in chain lines in Fig. 1 on downward

movement of the shaft 81 relative to the sleeve 73.

The shaft 81 is supported by a thrust bearing 86 formed in the hub 57 of the casting 54. A collar 87 secured to the shaft 81 by a key 88 transmits the load of the shaft to the thrust bearing.

The shaft 81 is preferably of square or other non-circular section, as shown in Figs. 3 and 4. The sleeve 82 has a cylindrical bore therethrough of such diameter as to permit rotation of the shaft therein. By virtue of the thrust bearings 74 and 86, rotation of the shaft 81 does not turn the block housing 25. The sleeve 73 turns on the thrust bearing 74 with the shaft 81, the lower portion of the bore through the sleeve being reduced and of square section to fit the shaft snugly.

The sleeve 82 is pivotally supported on trunnions 89 by a ring 90. The ring 90, in turn, is pivotally supported on trunnions 91 at right angles to the trunnions 89, in bearings 92 on the deck 18 of the trolley 10. The double-trunnion mounting of the sleeve 82 permits universal movement of the sleeve and the shaft 81 extending therethrough. It will be understood that the deck 18 has an opening of suitable size between the bearings 92 to permit the desired angular movement of the sleeve 82. Tension springs 82' secured to the lower end of the sleeve 82 and to any suitable anchorages on the trolley 10, serve normally to maintain the sleeve and the shaft 81 in substantially vertical position.

Adjacent the upper end of the sleeve 82, a gear case 93 is formed enclosing a worm wheel 94. The worm wheel 94 has a square hole thereto adapted to receive the shaft 81. A motor 95 is mounted on a shelf 96 extending laterally from the sleeve 82. The motor 95 is coupled to a shaft journaled in a gear case 97 and a pinion 98 is keyed on the shaft. The pinion meshes with a gear 99 on a worm shaft 100 in the case 97. A worm on the shaft 100 meshes with the worm wheel 94. A drive is thus provided for turning the shaft 81 in the sleeve 82. This permits the tongs 77 to be manipulated angularly as well as vertically in order that they may obtain the desired hold on an ingot when picking it up and may turn the ingot slightly in opposite directions when disposing it on the floor of the furnace in order that it may be firmly bottomed thereon.

The operation of the apparatus as a whole will probably be apparent from the foregoing description. In any event, Fig. 1 illustrates, in full lines, the up-raised, open position of the tongs 77. With the tongs in this position, the crane bridge 17 and the trolley 10 are operated along their track rails to "spot" the tongs approximately over an ingot to be picked up and charged into the soaking pit. The motor 42 is then energized to operate the drum 36, thereby lowering the block housing 25 without changing the relative positions of the castings 29 and 57. When the tongs have been positioned adjacent the top of the ingot, the motor 42 is stopped. The motor 64 is then started to drive the drum 62 in such direction as to pay out the cables 61. As already explained, this permits the casting 57 to descend in the housing 25. Since the weight of the shaft 81, which is considerable, is carried entirely by the collar 87 resting on the thrust bearing 86, the shaft descends with the casting 57. The tongs 77 thus move downwardly and are swung into gripping engagement with the ingot by the engagement of their rollers 84 with the sloping surfaces 85 on the sleeve 73. The

sleeve 73, of course, remains stationary as long as the drum 36 is stopped.

The weight of the shaft 81 is sufficient to cause tongs to engage the ingot firmly enough to permit lifting thereof and when such engagement has been secured, the motor 64 is stopped. Accurate stopping of the motor is unnecessary, however, since a slight amount of slack in the cable 65 will do no harm.

After securing a grip on the ingot, the crane operator starts the motor 42 to drive the drum 36 in such direction as to take up on the cables 35. This also takes up the cables 61 at the same rate, but the relative positions of the castings 29 and 57 are not altered, whereby the gripping engagement of the tongs on the ingot is not disturbed. The weight of the ingot is transmitted by the tongs to the surfaces 85 of the sleeve 73 and thence to the casting 29 and blocks 30 and 31.

When the ingot has been raised sufficiently to clear obstructions on the floor adjacent the soaking pit, the motor 42 is stopped and the girders 17 and trolley 10 are moved to bring the ingot over the pit. The motor 42 is then operated in such direction as to pay out the cables 35 and 61. The ingot is thus lowered into the pit, but since the relative positions of the castings 29 and 57 are still unchanged, the grip of the tongs on the ingot is not affected.

When the bottom of the ingot strikes the floor of the pit, the motor 42 is stopped. The motor 95 may then be operated for short periods in opposite directions to turn the shaft 81 and the tongs 77 as previously described, in order to bottom the ingot firmly on the pit floor. When this has been done, the motor 64 is operated to drive the drum 62 in such direction as to take up the cables 61. This raises the casting 57 and the shaft 81 relative to the casting 29 and sleeve 73, thereby permitting the gripping ends of the tongs 77 to swing outwardly and releasing the ingot. The motor 64 is then stopped and the motor 42 again operated to raise the castings, block and tongs out of the pit. Similar procedure is followed to remove an ingot from the pit.

Fig. 5 illustrates a modification in which shaft 81 extends through a guide 101 having a spherical enlargement 102 thereon disposed in a split spherical seat 103 on the deck 18 of the trolley 10. It will be apparent that the structure of Fig. 5 differs from that of Figs. 1 and 3 only in that in the former the ball-and-socket joint provided by the spherical enlargement 102 and the seat 103 constitutes a universal mounting for the guide 101, instead of the double-trunnion mounting of the guide 82.

It will be apparent from the foregoing description and explanation that the invention is characterized by numerous important advantages over soaking pit cranes as heretofore constructed. In the first place, the elimination of the conventional guide frame considerably reduces the weight and cost of the crane. A further advantage is that if the depending portion of the crane or an ingot in the tongs strikes an obstruction while moving, the suspended mechanism yields by swinging on its universal mounting, thereby saving the trolley and crane bridge from the impact stresses which would otherwise be transmitted thereto. The universal mounting of the vertical shaft, furthermore, makes it unnecessary to spot the tongs accurately relative to the ingot since no injury to the crane will result from lifting an ingot which is slightly off center relative

to the shaft. The only thing that will happen is that when the tongs close on the ingot, the shaft will swing slightly into alignment therewith. The motor for turning the tongs does not move up and down so it is unnecessary to provide long, flexible cables for supplying energy thereto.

The absence of the guide frame for the vertically moving portions of the crane gives the operator a good view of the tongs while standing on the deck 18 where he is protected to some extent from the heat of the furnace.

Although I have illustrated and described herein but a preferred embodiment of the invention with a modification of a portion thereof, it will be recognized that changes in the construction and arrangements of parts described herein may be made without departing from the spirit of the invention or the scope of the appended claims.

20 I claim:

1. A soaking-pit crane comprising a trolley adapted to move along a traveling bridge, a guide mounted on said trolley, a block housing suspended below the trolley, a shaft movable axially through said guide and housing, pivoted tongs adjacent the lower end of the shaft, a sheave block fixed in said housing, a tong-actuating member secured thereto, said shaft being slidable through said member and effective on movement relative thereto to open or close the tongs, a second sheave block movable in said housing, a collar secured to the shaft and bearing on said second block, cables traversing sheaves in both said blocks, a drum on the trolley, one end of the cables traversing the sheaves of both blocks being secured to said drum, and a second drum on the trolley, the other end of the cables traversing the sheaves of the movable block only being secured to said second drum, the other ends of the cables traversing the sheaves of the fixed block being anchored to said trolley, whereby operation of said first-mentioned drum raises or lowers both blocks simultaneously and operation of the second drum raises or lowers only the movable sheave.

2. A crane comprising a trolley, a shaft depending therefrom, a guide through which said shaft extends, means on said trolley mounting said guide for universal movement, tongs pivoted on said shaft, tong-actuating means carried below said trolley, said shaft being movable relative to said tong-actuating means, means on said trolley for raising and lowering said shaft to cause said tong-actuating means to open and close said tongs, and a motor and gearing mounted on said guide for rotating said shaft therein.

3. A crane comprising a trolley, a shaft depending therefrom, a guide through which said shaft extends, means on said trolley mounting said guide for universal movement, tongs pivoted on said shaft, tong-actuating means carried below said trolley, said shaft being movable relative to said tong-actuating means, means on said trolley for raising and lowering said shaft to cause said tong-actuating means to open and close said tongs, and means wholly mounted on said guide for rotating said shaft.

4. A soaking pit crane comprising a trolley, a guide, means on the trolley mounting the guide for universal movement, a shaft depending through said guide, pivoted tongs carried on said shaft adjacent the lower end thereof, a tong-actuating member adjacent said shaft, said member being effective on movement of the shaft relative thereto, means on said trolley for

raising and lowering said shaft and operating said member, a motor carried on said guide, and gearing driven by said motor effective to turn said shaft.

5. A soaking pit crane comprising a trolley, a sheave block disposed in a housing below the trolley, a shaft extending downwardly from said trolley through said housing, a bearing guide positioned on said trolley in which said shaft is slidable longitudinally, means mounting said guide for universal tilting movement, means wholly mounted on said guide for rotating said shaft, tongs carried on said shaft adjacent the lower end thereof, a tong-actuating member secured to said block, said shaft being movable through said block and effective on such movement to open or close the tongs, a second sheave block movably mounted in said housing, thrust bearing means whereby said second block supports said shaft, cables traversing sheaves in both said blocks, and means on the trolley for taking up or lowering selectively either or both said blocks.

6. A soaking pit crane comprising a trolley, a guide positioned on said trolley, means mounting said guide for universal tilting movement, a sheave block suspended below the trolley, a shaft extending downwardly from said trolley through

said guide and block, tongs carried on said shaft adjacent the lower end thereof, a tong-actuating member secured to said block, said shaft being axially movable through said guide and block and effective on such movement to open or close the tongs, means wholly mounted on said guide for rotating said shaft, a second sheave block suspended below the trolley, means whereby said second block supports said shaft, cables traversing sheaves in both said blocks, and means on the trolley for taking up or lowering selectively either or both said blocks.

7. A soaking pit crane comprising a trolley, a generally vertical sleeve mounted on the trolley, means supporting the sleeve for universal tilting movement, a shaft depending through said sleeve, pivoted tongs carried on said shaft adjacent the lower end thereof, a tong-actuating member adjacent said shaft, said member being effective on movement of the shaft relative thereto, means wholly carried on said sleeve for rotating said shaft therein, and suspension means for said shaft and member including means for raising or lowering the shaft and member together and means for raising or lowering said shaft relative to said member.

ROBERT J. HARRY.
